MACRAME BRACELET

Margaret M. Kronewitter, Rte. 3,
Edwardsburg, Mich. 49112

Filed Mar. 6, 1974, Ser. No. 448,522

Term of patent 14 years

Int. Cl. D11—01

U.S. Cl. D45—4 C

FIG. 1

FIG. 1 is a plan view of a macrame bracelet in extended condition, as seen from either the top or bottom, showing my new design; and

FIG. 2 is a side elevational view showing the bracelet in clasped condition.

I claim:

The ornamental design for a macrame bracelet, as shown and described.
